UNITED STATES PATENT OFFICE.

CHARLES J. HESSIAN, OF TIMONIUM, MARYLAND.

HOSE REEL.

Application filed February 4, 1925. Serial No. 6,836.

An object of the present invention is the provision of a novel reel for supporting the tube for conveying air to the tires of an automobile and novel means for supplying 5 the air from the pump to the reel and tube.

A further object of the invention is the provision of means for automatically winding up the air hose or tube on the reel after the same has been used.

10 A further object of the invention is the provision of a novel union for permitting the connection of the air outlet pipe of the pump with the rotatable shaft of the hose reel.

15 With these and other objects in view, the invention consists in the novel construction, arrangement and formation of parts, as will be hereinafter more specifically described, claimed and illustrated in the accompanying drawings, in which drawings,

20 Figure 1 is a longitudinal section through the novel union utilized for connecting the outlet pipe of the pump with the hub of the hose reel,

25 Figure 2 is a transverse section taken through the hose reel on the line 2—2 of Figure 3 looking in the direction of the arrows,

30 Figure 3 is a longitudinal section taken through the improved hose reel.

Referring to the drawings in detail, wherein similar reference characters designate corresponding parts throughout the several views.

35 A source of compressed air is adapted to have connected thereto a suitable hose 38 whereby the air can be conveniently conveyed to the tires to be pumped and in order to retain the hose in a compact condition

40 the novel reel 21 is provided therefor. This reel 21 comprises a casing 33 which is rigidly mounted on any preferred part of the chassis of the automobile and the side walls of the casing 33 rotatably support a hollow

45 shaft 34 to which is secured the drum reel proper 35. One end of the hollow shaft 34 is closed by a suitable cap 36, while the opposite ends thereof receive the novel union 37, which will be hereinafter more

50 fully described for connecting the outlet pipe 20 of the pump with the said hollow shaft 34. The hose 38 is adapted to be wound upon the hub 39 of the reel or drum 35 and is adapted to extend over a suitable

55 guide roller 40 carried by the reel casing 33 and through an opening 41 formed in the

front wall thereof. The sides 42 of the hub 39 are provided with gear teeth 43 for engagement with pinions 44 carried by the opposite terminals of a sleeve or hollow shaft 45 which is rotatably mounted on a stationary transversely extending shaft 46. It is to be noted at this point that the inner end of the hose 38 is connected by means of a nipple 47 with the hollow shaft 34 so that 60 air flowing into the shaft 34 will enter the said hose 38. A tension spring 48 is coiled about the stationary shaft 46 and has one end attached to the shaft and the other end to the hollow shaft or sleeve 45 and this 65 spring normally tends to wind or turn the sleeve or shaft 45 in one direction. It is obvious that when the reel or drum proper 35 is rotated as the hose is wound off of the same, that the sleeve or shaft 45 will 70 be rotated which will place the spring 48 under tension and that as soon as the hose is released, that the spring will tend to rotate the drum in a retrograde direction for 75 automatically winding up the hose. A stationary ratchet wheel 49 is secured to the rigid shaft 46 and this ratchet wheel is adapted to be engaged by a pivoted pawl 50 carried by the rotatable sleeve or shaft 45 and it thus can be seen that this shaft 80 or sleeve will function similar to an ordinary shade roller.

The improved union 37 utilized for connecting the stationary air outlet pipe 20 of the pump with the rotatable shaft 34 of the 85 reel proper or drum 35 embodies a nipple 51 which is threaded into engagement with the end of the shaft 34 opposite to the end which receives the cap 36. The outer end of the nipple 51 has formed thereon a flange 52 which is received within a threaded cap 53. This cap 53 receives a hollow plug 54 which is threaded into the same. The plug 54 is threaded into the cap 53 until in engagement with the flange 52 and a suitable packing 55 can be placed in the cap between the inner wall thereof and the plug and around the said flange 52 and nipple 51. The outer end of the plug 54 is supported by the air outlet pipe 20 of the pump 90 and is threaded thereon. It therefore can be seen that air is permitted to flow through the outlet pipe 20 into the bore of the plug 54 and then into the rotatable nipple 51. By this construction the nipple is free to 95 rotate within the cap 53 and no air will be lost.

Changes as to details may be made without departing from the spirit or the scope of this invention, but:—

What I claim as new is:—

- 5 In a hose reel of the character described, a hollow shaft structure, means for rotatably supporting the same, a hose reel mounted on said shaft, and comprising a hollow hub through which said shaft extends and disc end plates carried by said hub, gear teeth formed about the periphery of said end plates, a rigid shaft mounted in parallel relation to said hollow shaft, a sleeve body mounted upon and having said rigid 10 shaft extending through the longitudinal

center thereof, a coil spring encircling said rigid shaft, within said sleeve and having one end connected to the shaft, and the other end connected to the sleeve, a gear member carried by said sleeve adjacent each end thereof, and meshing with the teeth of an adjacent one of said end plates, and means leading from the interior of said hollow shaft, to and through said hub body, for conducting the fluid from the hollow shaft 25 to a hose mounted upon the hub body substantially as and for the purpose described.

In testimony whereof I affix my signature.

CHARLES J. HESSIAN.
